CENTRIFUGAL SWITCH

Lloyd W. Young, Elizabeth, N. J., assignor, by
mesne assignments, to Union Carbide and Car-
bon Corporation, a corporation of New York

Application January 19, 1935, Serial No. 2,496

11 Claims. (Cl. 200—80)

The invention relates to electric switches and more particularly to control devices such as centrifugal switches of the type employed for controlling the speed of electric motors.

5 When an electric motor is employed to drive a machine that operates at various specific uniform speeds, these speeds may be produced by controlling the speed of the driving motor, but the devices employed heretofore for controlling the 10 speed of such motors have not been entirely satisfactory. For example, the size of such devices has been too large or the life too short for practical application, and therefore, one of the objects of this invention is to provide a control device 15 of the type described that is more compact and at the same time has a longer operating life.

Heretofore, centrifugal switches of this type have not been dynamically balanced with sufficient accuracy to prevent annoying vibration 20 while in use, especially at the higher operating speeds, and unduly rapid deterioration of the motor bearings and switch elements which are subject to this vibration. Therefore, another object is to provide a switch of this type that is 25 dynamically balanced to a high degree so that operation at a relatively high speed will not cause deterioration or injury to either the switch or the motor with which it cooperates.

In prior devices of this kind the centrifugal 30 mechanism has not been sufficiently sensitive to small changes in speed to prevent undesirable fluctuations in the speed of the controlled motor, and therefore another object of this invention is to provide a control device of the type described 35 that will maintain a more nearly constant motor speed. Also, due to manufacturing variations in the component parts, as well as variations in the characteristics of the materials employed, prior devices have not accurately produced a suitable 40 range of predetermined speeds. Therefore, another object of this invention is to provide a device of the class described that will more accurately produce a suitable range of predetermined speeds which are clearly marked on the adjusting 45 mechanism.

Prior devices of this kind have also been subject to comparatively rapid deterioration due to wear between the rotating and the stationary co-operating parts, and therefore another object is 50 to provide a device of this type in which the wear between relatively moving parts is reduced to substantially that of the other wearing surfaces of the machine with which it is connected.

In control switches of this type the control contacts often make and break the operating current

of the controlled motor at a comparatively rapid rate, and this tends to cause overheating and burning of the contacts which materially shortens their life. Consequently, the contacts in prior devices have been undesirably large in size or 5 undesirably short in life. Therefore, another object is to provide a device of this kind in which the contacts are provided with means for preventing this burning so that they may be small in size and at the same time long in life. Other 10 objects are to provide a device of the type described with an extremely sensitive centrifugal element and means for preventing this element from becoming damaged when rotated at relatively high speed. Another object is to provide 15 such a device with a centrifugal element that may be readily manufactured. A further object is to provide such a device with an adjustable indicating member bearing a scale indicating motor speeds or factors thereof, and means for 20 coordinating these speeds or factors with corresponding motor speeds so that an individually calibrated scale for each device is obviated.

Other objects are to provide such a device that is efficient and accurate in action, long in life, 25 easy and convenient to manipulate, and in which the component parts are interchangeable. These and other objects and novel features will be apparent from the following description and the 30 accompanying illustration, in which:

Fig. 1 is a longitudinal sectional view of a centrifugal switch embodying my invention secured to one end of an electric motor which forms no part of the invention and therefore is not shown in section;

Fig. 2 is a transverse sectional view of the above-mentioned switch taken along line 2—2 of Fig. 1 showing the structure, arrangement, and support for the electric contacts; and

Fig. 3 is a transverse sectional view of the 40 above-mentioned switch taken along line 3—3 of Fig. 1 showing the connection between the motor and the contacts.

The invention shown by the drawing may be embodied in a centrifugal switch comprising a 45 dynamically balanced centrifugal A that cooperates with an interrupter B which may be moved with respect to the centrifugal by adjustable indicating means C to vary the operating point of the interrupter with respect to the speed of the 50 centrifugal.

The centrifugal A may consist of a cylindrical disk or rotor 10 of suitable material such as a metal, of which brass is desirable from the standpoint of the ease with which it may be machined. 55

For the purpose of attaching the movable elements of the centrifugal the rotor 10 may be provided with diametrically opposed identical slots 12 of which the bottoms slope outwardly from each 5 face of the rotor at a suitable angle. Although the angles may vary according to the type and operating speed of the centrifugal it has been found satisfactory to slope the portion 14 of the bottom adjacent the outer face of the rotor outward at an angle of substantially 30° from the 10 axis of the rotor, and to slope the portion 16 of the bottom adjacent the inner face of the rotor outward at an angle of substantially 60° from the axis of the rotor. Also, although the relative 15 length of the slopes 14 and 16 may vary, a suitable proportion may be obtained when slope 14 is substantially twice the length of slope 16.

The resilient portion of the centrifugal may consist of a bowed spring such as a substantially 20 elliptical spring 18 with its long axis transverse to the axis of rotation and having inturned ends of which each may be provided with a suitable opening by which it may be secured to one of the slopes 16 by means of a suitable fastening such 25 as a drive screw 20. The bowed central portion of spring 18 may be spaced from the outer face of rotor 10, and each end may lie within the outer end of one of the slots 12 a suitable distance from its sloping bottom portion 14 and an equal 30 distance from the axis. To prevent friction between the spring 18 and the rotor 10 the width of the spring may be somewhat less than the width of the slots 12, and to more securely hold the spring 18 in correct alignment and dynamic balance 35 with the rotor the slopes 16 may be suitably grooved to receive the ends of the spring. To operate the spring 18 the space in each of the slots 12 within each elliptical end of the spring 18 may be provided with a suitable weight 22 that is 40 movably mounted with respect to both the rotor and the spring and fits loosely between the side walls of the slot so that it is free to move outward under the influence of centrifugal force and exert pressure upon the inner surface of spring 18. 45 Although any suitable weights may be employed steel balls such as bearing balls have been found desirable on account of their extreme accuracy in size and weight, and their accurate balance when properly positioned. The relative size of 50 the weights 22 and the strength of spring 18 may vary according to the range of operating speeds and sensitiveness desired, but in the present construction a comparatively high degree of sensitiveness to slight changes in speed has been obtained by employing weights $\frac{1}{8}$ in. in diameter 55 and a spring of steel, such as a clock spring, $\frac{1}{16}$ in. in width and .010 in. in thickness.

In devices of this kind a centrifugal that is sensitive to slight changes in normal operating 60 speeds may be injured at higher speeds. In the present construction however, this contingency is obviated by providing the centrifugal with a buffer spring 24 that limits the travel or deformation of spring 18 and prevents such injury. This 65 spring 24 may be a helical spring located between the rotor 10 and spring 18 and one end may be secured in an annular groove 26 in the outer face of rotor 10 by suitable means such as frictional engagement with the walls thereof, and the other 70 end may be provided with an abutment member 28 frictionally secured to the spring and having an outer face spaced a short distance from the inner face of spring 18 when this spring is not deformed by centrifugal force.

75 As the purpose of this centrifugal switch is to

control the speed of an electric motor it may be secured directly to one end of the motor with which it cooperates. To this end the rotor 10 may be provided with an axial opening 30 at the center of weight and of suitable size to properly fit 5 upon the projecting outer end of a shaft 32 of an appropriate motor 34. The rotor 10 may be secured in this position on shaft 32 by appropriate conventional means such as a set screw 36. When only one set screw is employed, and this 10 screw does not entirely fill the opening in the rotor in which it is located, an opening may be provided in the opposite side of the rotor substantially the same size as the unfilled portion of the 15 opening in which the set screw is located in order to more easily preserve the accurate balance of the rotor.

The centrifugal A may be inclosed in a suitable 20 casing 38 which for convenience may be in the form of a hollow cylinder provided with a suitable number of inturned ears 40 by which it may be secured to the end of motor 34 by suitable conventional fastening such as a plurality of 25 screws 42. The inner cylindrical wall of casing 38 may be spaced from the centrifugal a suitable 30 distance to allow for expansion of spring 18 and also for conductors connecting the switch with the motor. Also, the casing may be of suitable length to provide space for the interrupter.

The interrupter B may consist of a pair of suitable 35 contacts 44 and 46 respectively secured to appropriate springs 48 and 50 that are secured to a dielectric terminal block 52 by conventional means such as bolts 54. This terminal block may be secured to casing 38 by suitable hinges or pivots 40 such as a pair of resilient conductors 56 and 58 each having an overturned end secured to the terminal block by one of the bolts 54 and an overturned end adjacent the end of motor 34 to which a suitable conductive wire may be secured. These 45 conductors 56 and 58 may be secured to the inner surface of casing 38 by an overlying clamping member 60 which in turn may be secured to the casing by a suitable fastening such as one or more screws 62, and these conductors may also be insulated from the casing by suitable dielectric material such as an appropriate length of varnished insulating tubing 64 in which they may be 50 closed.

For the purpose of securing proper cooperative 55 relation between the contacts 44 and 46, one of the contact springs, such as 48, may be secured to the side of contact block 52 facing the centrifugal A, and the other spring, such as 50, may be secured to the side opposite the centrifugal. Also, to secure suitable cooperative relation between the centrifugal and the interrupter, spring 48 may cross the axis of the centrifugal and this 60 spring may be provided with a suitable mechanical contact bearing button or thrust button 66, of appropriate wear resisting dielectric material 65 such as fiber located in alignment with the axis of the centrifugal. During operation the rotating spring 18 bears upon the thrust button 66 with sufficient pressure to operate the contacts, and the wear between these relatively moving parts may be reduced to a negligible minimum 70 by providing this thrust button with an insert 68 of suitable lubricating material such as graphite or the like.

Also, during operation, the contacts 44 and 46 75 may interrupt the operating current of motor 34 at a relatively rapid rate, and this continuous interruption tends to generate considerable heat at the contacts which, if not dissipated, may cause 75

- relatively rapid deterioration. In the present construction, however, the heat generated at these contacts may be dissipated or radiated by providing heat conducting members, such as washers 5 70, in heat exchange relation with the contacts. These heat radiating members may be of metal having a high conductivity of heat, such as copper, and they may be of somewhat larger size than the contacts or contact supporting springs. 10 For convenience in mounting these washers may be secured to the contact springs on the side opposite the contacts by providing the contacts with supporting shanks or stems of sufficient length to extend through a supporting spring and one 15 of the heat dissipating members where the end of the shank may be upset, overturned, or riveted to secure the assembly together.

The outer end of casing 38 may be closed by suitable means such as adjustable indicating 20 means composed of a cap 72 which may be movably mounted on the casing by appropriate co-acting formations such as interfitting threads 74 on the outer surface of the casing and the inner surface of the cap, and suitable operating connection 25 may be provided between this cap 72 and the interrupter B so that the position of the interrupter with respect to that of the centrifugal may be changed by movement of this cap to vary the operating point of the interrupter with respect to 30 the speed of the centrifugal and thereby vary the speed of the controlled motor.

For this purpose the cap 72 may be provided with an adjusting plate 76 in operative relation 35 with a cooperating adjusting button 78 which may be carried by a relatively rigid contact adjusting arm 80 rigidly secured to terminal block 52 by a conventional fastening such as screw 82. The relative position of cap 72 with respect to 40 casing 38 may be indicated by a scale graduated in rotative speeds of motor 34 or some factor dependent upon the speed of the motor. This scale may be carried by either the cap or the casing, but for convenience of manufacture a separate scale 84 may be provided which extends substantially 45 around the periphery of cap 72. For purpose of appearance this scale may be embedded in an appropriate circumferential groove in the outer surface of the cap 72, to which it may be secured by suitable fastening such as one 50 or more rivets, pins, or drive screws 86. As the entire range of motor speeds desired may be secured by one revolution of cap 72, it may be limited to this range of movement by providing the cap and casing with suitable stops such as a 55 lug 88 extending outward from the end of casing 38, and a cooperating screw 90 extending inward from the inner surface of cap 72.

In order to adjust the speed of motor 34 to some particular speed factor, for example, the 60 lowest shown by scale 84, means may be provided for adjusting the operating point of the interrupter with respect to the speed of the motor by varying the position of plate 76 with respect to that of cap 72. This may be accomplished by 65 providing plate 76 with a threaded stem or shank 92 that extends outwardly through a correspondingly threaded opening in cap 72 at a suitable point such as the axis where it may be secured against inadvertent movement by a lock nut 94. 70 In addition to this adjustment, means may be provided for varying the ratio of movement between the cap and the interrupter to secure proper coincidence between the other speed factors shown by scale 84 and corresponding motor 75 speeds. This may be accomplished by providing

means for adjusting the distance of adjusting button 78 from the fulcrum around which the interrupter moves. To secure this adjustment, adjusting arm 80 may be provided with a series of openings 96 at various distances from the resilient ends of conductors 56 and 58, which form a fulcrum for the interrupter, and adjusting button 78 may be secured in any one of these openings found necessary to secure the degree of coincidence desired. 10

For purpose of operation the contacts of the centrifugal switch may be connected in series with the electric circuit of the motor, and this may be conveniently accomplished by connecting one of the motor conductors, such as 98, with 15 one of the switch conductors, such as 56, and then providing the other switch conductor, such as 58, with an electric conductor or wire such as 100 that extends to the outside of the switch casing where this conductor together with the 20 other motor conductor 102 may be conveniently connected with a supply circuit.

These connections may be made by bringing the motor conductor 98 into the switch casing through a suitable opening and then connecting 25 this conductor, by suitable means such as solder, with the overturned inner end of switch conductor 56. Conductor 100 may also be brought into the switch casing through the same or a similar appropriate opening and then connected 30 with the inner overturned end of switch conductor 58 by similar suitable means.

Although the weights 22 are not rigidly secured 35 to the rotor 10 they are held diametrically opposite each other by the slots 12. When the rotor 35 is rotating these weights lie against the inside of the outer ends of spring 18 which are equal distances from the axis of the rotor, and this, together with the fact that the weights are exactly alike, produces a centrifugal that is dynamically balanced and imparts no appreciable vibration to the motor or the switch. Furthermore, for the reason that the spring 18 is secured to the rotor at a point closely adjacent each of the portions that control the position of the weights, any 40 deformation of the spring during operation does not move the weights out of dynamic balance even at relatively high operating speeds, and any tendency toward such movement is restricted to such an extent that it is not appreciable by the fact 45 that the spring 18 is of such a form that the weights move a relatively small amount in proportion to the axial or operating portion, and by the fact that the movement of this portion of the spring is limited by the buffer 24 to that necessary 50 to operate the contacts. 55

During the operation of the apparatus just described, the centrifugal force of the revolving weights 22 expands the looped spring 18 and draws the central portion at the axis of the rotor 60 in a direction away from the interrupter various distances according to the speed of rotation. When springs 48 and 50 are in free condition contacts 44 and 46 are separated a sufficient distance to break the motor circuit, although when 65 the motor is idle or rotating at a speed below that indicated by the scale 84 the contacts are held together by the pressure of spring 18 upon the button 66 carried by contact spring 48. Thus, when the motor speed increases to that indicated 70 by the scale 84 the closing pressure of spring 18 is withdrawn from the contacts 44 and 46 and they are separated by the resiliency of their supporting springs 48 and 50 thereby opening the motor circuit. Therefore, the speed of the motor 75

is maintained at substantially that indicated by the scale.

Due to the more or less elliptical shape of spring 18, the central portion which operates the contacts moves a relatively large amount in proportion to changes in speed of rotation, and this movement is imparted to the contact supporting springs at a point much nearer the fulcrum than the contacts, the contacts are moved a relatively large amount in proportion to the movement of spring 18, and therefore this centrifugal switch maintains the motor at a more constant and accurate speed than devices of this kind known heretofore in which the centrifugal was less sensitive and the operating contacts moved at the speed of the controlling portion of the centrifugal. Also, as the entire contact assembly or interrupter is moved as a unit with respect to the centrifugal by movement of the speed adjusting member, the contact separation remains constant and the resistance of contact spring 48 to the contact closing pressure of the centrifugal remains constant and uniform throughout the range of adjustment and this tends to further increase the sensitivity of the switch and its accuracy of operation.

When prior devices of this kind are adjusted to a relatively high speed and the motor is idle or operating at a speed below the setting of the adjustment, the centrifugal exerts a relatively high degree of pressure upon the bearing surface between the rotating centrifugal and the stationary contacts as well as upon the contacts and their supporting structure. This tends to cause rapid wear upon the bearing surface and undue deterioration of the contacts and their supports. In the present structure, however, these undesirable conditions are obviated by mounting both contact supporting springs 48 and 50 so that they are free to flex in response to closing pressure or movement greater than that required to flex one spring and close the contacts, and therefore the bearing pressure between the centrifugal and the contacts is sufficiently low to prevent undue wear and rapid deterioration, and the pressure upon the contacts and their supporting springs is not high enough to cause injury or changes in adjustment or operation.

The scale 84 may be graduated to directly indicate the speed of the controlled motor or any factor or result dependent upon the motor speed. Also, the form, shape, and relative position of the component parts may be different from that shown, and other suitable materials and conventional or well known elements may be substituted for those described without departing from the scope of the invention or the advantages derived therefrom.

I claim:

1. A centrifugal switch comprising a centrifugal adapted to be rotated; a pair of cooperating electric contacts in operative relation with said centrifugal and in series with an electric circuit; a pivot for supporting said contacts; and means for moving said contacts around said pivot to vary the distance between said contacts and said centrifugal and thereby control their cooperating influence.

2. A centrifugal motor speed governor comprising a casing; a centrifugal within said casing adapted to be rotated by a motor; a pair of cooperating contacts within said casing in operative relation with said centrifugal and suitably connected in series with the operating circuit of said motor; an adjusting member movably

mounted upon said casing for varying the relative position of said contacts with respect to said centrifugal for varying the speed of said motor; a scale in operative relation with said adjusting member for indicating the speed of said motor; and means movably mounted on said adjusting member for initially varying the contact pressure of said contacts to secure coincidence between the speed of said motor and that indicated by said scale. 10

3. A centrifugal motor speed governor comprising a casing; a centrifugal within said casing adapted to be rotated by a motor; a pair of cooperating contacts within said casing in operative relation with said centrifugal and 15 suitably connected in series with the operating circuit of said motor; an adjusting member movably mounted upon said casing for varying the relative position of said contacts with respect to said centrifugal for varying the speed of said 20 motor; a scale in operative relation with said adjusting member for indicating the speed of said motor; and means for varying the ratio of movement between said adjusting member and said contacts to secure coincidence between the speed 25 of said motor and that indicated by said scale throughout the range thereof.

4. A centrifugal switch comprising a casing; a centrifugal within said casing; a pair of cooperating contacts within said casing in operative 30 relation with said centrifugal; an adjusting member rotatably mounted with respect to said casing for varying the relative position of said contacts with respect to said centrifugal to vary the operating point of said contacts with respect 35 to the speed of said centrifugal; and cooperating means on said casing and on said adjusting member for limiting the movement of said adjusting member to substantially one revolution.

5. A centrifugal switch comprising a rotor; a 40 substantially elliptical spring operably secured to said rotor; a suitable weight in operative movable relation with the inner surface of each elliptical end of said spring; and a pair of electrical contacts in operative relation with said 45 spring.

6. A centrifugal switch comprising a rotor; a substantially elliptical spring operably secured to said rotor with its long axis transverse to the axis of said rotor; a suitable weight in relatively movable relation with the inner surface of each elliptical end of said spring; and a pair of electrical contacts in operative relation with said spring. 50

7. A centrifugal switch comprising a rotor; a 55 substantially elliptical spring operably secured to said rotor; a weight movable with respect to said spring and said rotor in operative relation with the inner surface of each elliptical end of said spring; and a pair of electrical contacts in 60 operative relation with said spring.

8. A centrifugal switch comprising a centrifugal composed of a cylindrical rotor provided with diametrically opposed slots in the outer portion thereof; a substantially elliptical spring having 65 one end thereof secured in and substantially closing the outer end of each of said slots; a pair of cooperating electric contacts operatively associated with said elliptical springs; and a bearing ball movably mounted in each of said slots 70 in operative relation with the inner surface of said spring.

9. A centrifugal switch comprising a centrifugal composed of a rotor; a pair of weights rotatable with said rotor; a spring secured to said ro- 75

5 tor in operative relation with said weights so that said spring may be deformed by the centrifugal force exerted by said weights; a pair of cooperating electric contacts operatively associated with said springs; and a buffer spring secured to said rotor to limit the deformation of said first mentioned spring.

10. In a centrifugal switch, the combination of a rotary element adapted to be deformed a varying amount according to the speed of rotation; a circuit interrupter operable by the deformation of said rotary element for controlling the speed thereof and movable with respect to said rotary element to vary the speed thereof; 15 adjustable indicating means movable with said interrupter for varying the speed of said rotary element by varying the relative position of said interrupter with respect to said rotary element; and means for varying the ratio of movement 20 between said interrupter and said indicating means for securing coincidence between the speed of said rotary element and those indicated by said indicating means throughout the range of speeds indicated thereby.

11. In a centrifugal switch, the combination of a rotary element adapted to deform a varying amount according to the speed of rotation; a circuit interrupter operable by the deformation of said rotary element for controlling the speed thereof and movable with respect to said rotary element to vary the speed thereof; adjustable indicating means movable with said interrupter for varying the speed of said rotary element by varying the relative position of said interrupter with respect to said rotary element; means for varying the relative position of said interrupter with respect to said indicating means for securing coincidence between the speed of said rotary element and a particular speed indicated by 15 said indicating means; and means for varying the ratio of movement between said interrupter and said indicating means for securing coincidence between the speed of said rotary element and those indicated by said indicating 20 means throughout the range of speeds indicated thereby.

LLOYD W. YOUNG.
